AIR COOLING AND WASHING DEVICE

Yaichi Hayakawa, Chicago, Ill.

Application December 19, 1932, Serial No. 647,974

2 Claims. (Cl. 261—29)

This invention relates to certain novel improvements in air cooling and washing devices, and has for its principal object the provision of an improved construction of this character which will be highly efficient in use and economical in manufacture.

An object of this invention is to provide a new, compact, portable, relatively simple and inexpensive air cooling and washing device.

10 Other objects will appear hereinafter.

The invention consists in the novel combination and arrangement of parts to be hereinafter described and claimed.

The invention will be best understood by reference to the accompanying drawings, showing the preferred form of construction, and in which:

Fig. 1 is a top plan view of the invention;
Fig. 2 is a vertical sectional view on line 2—2 in Fig. 3;

20 Fig. 3 is a side elevational view, on line 3—3 in Fig. 2, with a part of the wall of the air washing chamber broken away to show the cooling unit therein;

Fig. 4 is a view on line 4—4 in Fig. 2, partly in 25 bottom plan and partly in section;

Fig. 5 is a view on line 5—5 in Fig. 2, partly in top plan and partly in section;

Fig. 6 is a fragmentary vertical sectional view 30 of the air blower and water pump embodied in the device;

Fig. 7 is a sectional view on line 7—7 in Fig. 6;
Fig. 8 is a sectional view on line 8—8 in Fig. 6;

Fig. 9 is a sectional view on line 9—9 in Fig. 6; and

35 Fig. 10 is a sectional view on line 10—10 in Fig. 9.

In the drawings 10 indicates generally a casing, the interior of which provides an air cooling and washing chamber 11. This casing 10 includes a lower section 12 which provides a water tank and an upper section 13 mounted thereon. Arranged in the air washing and cooling chamber 11 is a gas or vapor expansion coil 14, the ends 40 of which are led outside the casing (Figs. 3 and 5) for connection to a suitable refrigerating unit.

Mounted on the top wall of the casing 10 is a blower 16 over which is arranged a housing 17. The blower 16 is operated by an electric motor 50 20, also mounted on the top of casing 10. The housing 17 has an inlet 18 which is provided by a ring 21 attached thereto (Fig. 6), and through this inlet 18 air is sucked, in the use of the device, into the blower 16. The bottom of the housing 17 communicates with the chamber 11 through

an opening 19 formed in the top wall of the casing 10, so that the air drawn in through the inlet 18 by the blower 16 is blown thereby through the opening 19 into the cooling and washing chamber 11, from which it is directed out through the outlet 22 to distribution pipes or directly to the room area, as desired.

The motor 20 which operates the blower 16 also operates, through a clutch 23 and a system of gears 24, a dual piston pump, generally indicated at 27. This pump is mounted in a housing 25 arranged in the casing 10. When the motor 20 and blower 16 are in operation the pump 27 sucks water up from the tank section 12 of the casing 10 by way of the pipe 26 from 15 which the water flows into the pump 27, thence out of the pump by way of pipe 28 to an overflow housing or reservoir 29; from the housing 29 through a pipe 30 into a distributor passage 31 formed in the ring 21 (Fig. 8); and from the distributor passage 31 through a series of branch passages or nozzles 32, formed in the ring 21, and which direct the water into the blower 16 to be commingled thereby with the air sucked into the blower through the inlet 18.

A pipe 33 leads from the upper chambered portion of the overflow housing valve 29 into the distributor passage 31. If the pump 27 is supplying water to the line 28—30 faster than the same can be injected into the blower 16 through 30 the branch passages or nozzles 32, the water will rise into the upper chambered portion of the overflow housing 29, and should the housing 29 fill up to the level of the pipe 33 it will then overflow through pipe 33 into the distributor 35 passage 31. The upper chambered portion is provided with an open top that is closed by a pivoted cap, as best shown in Fig. 9, so that if the flow should become too great to prevent a uniform flow through the nozzles 32, it will force 40 the cap open and relieve the pressure, with the result it will be seen that the overflow housing also acts in the capacity of a relief valve.

The pump 27 is operated from the motor 20 by a conventional clutch and gear mechanism 45 23—24, which is constructed as follows: On one end of the motor shaft 34 is a worm 35 (Figs. 6 and 9) which meshes with a gear 36 that is fast on a vertical shaft 37. On the shaft 37 is a worm 38 (Figs. 9 and 10) which meshes with a gear 39 which is fast on a horizontal shaft 40. Formed on this gear 39 is a clutch face 41. Fast on the shaft 40 is a clutch face 42 and floating on the shaft 40 between the clutch faces 41 and 42 is a gear body having gears 43 and 44 of dif- 55

ferent diameters formed thereon; said gear body having a clutch face formed in each end thereof.

Arranged parallel to the shaft 40 is a crank shaft 45 on which are fast gears 46 and 47. Attached to the crank shaft 45 at its ends are throws 49 that are spaced from each other relative to the circumference of the crank shaft 45. Operatively connected to the throws 49 are connecting rods 50 that are attached at their lower ends to flexible diaphragm pistons 51. These pistons work alternately in the cylinders 52 of the pump 27, by reason of the spacing of the throws 49. The cylinders 52 are interconnected by a pipe 53 which leads into the pipe 28, (Fig. 4).

15 The water supply pipe 26 opens by way of a branch passage 54 (Fig. 9) into the bottom of each of the two pump cylinders 52, and in each branch passage 54 is a ball check valve 55. Each of the cylinders 52 communicates with the T 53 by way of a passage 56 (Fig. 6), and in each of these passages 56 is a ball check valve 57.

20 The speed of the pump 27 may be varied by shifting the pivotal clutch shift lever 48 (Figs. 9 and 10) so as to mesh the gear 43 with the gear 46, or to mesh the gear 44 with the gear 47.

25 The speed of the motor 20 and blower 16 may be varied by means of a suitable variable resistance or rheostat 58 arranged in circuit with the motor.

30 Operation: The motor 20 is set in operation and the same drives, directly, the blower 16 (Fig. 6). At the same time the motor 20 operates the pump pistons 51 through the clutch and gear systems 23 and 24, which are of conventional design, as hereinbefore stated and described (Figs. 6, 9 and 10). The pump pistons 51 are alternately reciprocated up and down, and on the suction or up stroke of each piston 51 sucks water into the corresponding cylinder 52, from the tank 12 35 of casing 10, by way of the water supply line 26—54 and the corresponding ball check valve 55. On the down stroke of each piston-diaphragm 51, the corresponding ball check valve 55 reseats and closes by gravity and the downwardly 40 moving piston forces the water out of the cylinder 52 through the corresponding passage 56 and ball check valve 57 into the T 33; thence through the pipe 28, through overflow valve 29, through the pipe 30 into the distributor passage 45 31 and from the passage 31 through the branch passages or nozzles 32 into the blower 16, to be commingled thereby with the air sucked into the blower through the inlet 18. The blower 16 blows the commingled air and water vapor into and circulates it through the chamber 11, wherein it circulates around the expansion or cooling coil 14, and finally the action of the blower 16 forces the 50 cooled and washed air out of the chamber 11, 55

by way of the outlet 22, to the room area or to distribution pipes, as desired.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. An air cooling and washing device, comprising the combination of a casing including a lower section providing a water tank and an upper section mounted upon the lower section and together with the latter providing an air cooling and washing chamber having an outlet, an air cooling unit in said chamber, a blower, a housing for the blower having an outlet below the blower opening into the upper section of said chamber, a member providing an inlet into said blower housing and having formed therein a distributor passage and a series of branch passages leading from said distributor passage into said inlet, means providing a water-conducting passage having an inlet in the chamber and an outlet into said distributor passage, a dual pump for forcing water through said water-conducting passage from the chamber to the distributor passage, and a single power unit for simultaneously operating the blower and the pump.

2. An air cooling and washing device, comprising the combination of a casing including superimposed sections mounted for communication one upon the other, the lower section providing a water tank and together with the remaining portion of the casing providing an air cooling and washing chamber having an outlet in its top, an air cooling unit in said chamber, a blower mounted upon said top, a housing for the blower having an outlet opening into the top of said chamber, a member providing an inlet into said blower housing, said member having formed therein an annular distributor passage and a series of branch passages radiating from the distributor passage into said inlet, means providing a water conducting passage having an inlet in the chamber and an outlet into said distributor passage, overflow means in the water conducting passage, a dual pump for forcing water through said water-conducting passage from the chamber to the distributor passage, and a single power unit for simultaneously operating the blower and the pump.

YAICHI HAYAKAWA.
